LIPSTICK HOLDER

Charles M. Tursky, Englewood, N. J.

Application January 10, 1947, Serial No. 721,251

11 Claims. (Cl. 206—56)

1

This invention is an improvement in holders for cosmetics, and more particularly a holder for lipstick comprising a casing for the lipstick and means for causing the latter to protrude from the casing when needed, and then to be withdrawn into the casing so as to be kept in readiness for further use.

In my prior application for patent on a cosmetic pencil holder, Serial No. 697,549, filed September 17, 1946, I have disclosed a casing for lipstick that is round in cross section, with a lipstick inside, means for mounting and actuating the lipstick to project and withdraw the same and a shutter valve at one end of the casing to permit exposure of the end of the lipstick and shield said end when the lipstick is retracted into the casing. The objects of this invention are in general the same as those of the invention of my said prior application; but it is also my present purpose to provide a lipstick that is other than round in cross section, relatively simple in design and consisting of few parts, comparatively inexpensive to produce and very easy to handle and operate.

The nature and advantages of the invention are set out in the following disclosure and the novel features are defined in the appended claims.

On the drawings showing an embodiment of the invention,

Figure 1 is a view in elevation of a lipstick holder according to this invention, as it appears when the holder is closed, and seen from one side thereof.

Figure 2 is a front elevation thereof.

Figure 3 is a rear elevation of same.

Figure 4 is a view of the device as it appears when the observer looks down on the top thereof as presented in Figure 1.

Figure 5 is a detail view of the front end of the holder as shown in Figure 4, with the lipstick protruding.

Figure 6 is a front view in elevation similar to Figure 1, with the lipstick protruding, as in Figure 5.

Figure 7 is a sectional view of the holder on the line 7—7 of Figure 6.

Figure 8 is a similar view with the holder open at its front end and the lipstick ready for use.

Figure 9 is a view in cross section on line 9—9 in Figure 1.

Figure 10 is a cross section on line 10—10 of Figure 7; and

Figures 11, 12 and 13 are perspective views of some of the separate parts of the device.

The holder comprises a casing 1; preferably

2

rectangular in cross section, with two wide faces, one of which is shown on Figure 1 and two narrower faces, one of which is presented on Figure 4. Inside is a hollow sleeve or carrier 2 in the form of a rectangular tube, open at both ends, into which is inserted a lipstick 3 of the same cross sectional outline, the sleeve being mounted for movement in the casing 1 to project the extremity of the lipstick out of the casing past a bivalve-like closure or shutter consisting of two matching pivoted shell-shaped sections at one end of the holder, with curved front walls 4; and in the opposite direction to withdraw and enclose the lipstick 3 when it is not needed. The casing 1 and sleeve 2 also contain means for feeding the lipstick forward as it is consumed; but I shall first describe the shutter, and the method of supporting and operating the latter.

Each section of the closure as best depicted on

Figure 13, has two parallel opposite sides 5, the two sections when closed abutting along straight parts 6 of the edges of the sides adjacent the front thereof. Parts 7 of the edges of the two sides 5 of each section opposite the edges 6 are curved at the forward ends of the sections, these curved parts intersecting the straight edges 6, at the front of each section, and being spanned by the walls 4. The latter terminate near the middle of the sides 5; and bridging the sides 5 of each section just aft of the rear edges of the curved front walls 4 thereof is a fixed bar 8. This bar is rectangular in cross section for a purpose that will appear later herein.

The two sides 5 of each section are extended back past the bar 8, terminating at the rear in triangular portions 9, having rounded extremities and one edge of each connected to the edge 6, but making an angle therewith. The opposite edges of the terminal parts 9 are continuations of the edges 7 and are substantially parallel to the edges 6. When the two sections are mounted in the open front end of the casing 1, the edges 6 of one section, when the holder is closed, abut the edges 6 of the other, the sides 5 of one section being flush with the sides 5 of the other; and when the closure is actuated to open position, the adjacent edges of the rear parts 9 of the sides 5 come into contact, with the curved walls 4 in front separated as shown in Figures 6 and 8.

The inner end of the lipstick 3 within the sleeve 2 is engaged by a rectangular piston 11 which has a threaded hollow rod or stem 12 extending towards the rear end of the casing 1. This stem has a round longitudinal bore 13. On the stem 12 is a threaded adjusting element in the form of

a long hollow screw 14. This screw can turn in the sleeve 2, but has, near its rear end, an outside projection or collar 15 that engages two apertures 16 in opposite sides of the sleeve 2. The screw 14 therefore cannot move longitudinally in the carrier 2, but can be rotated therein. The sleeve 2, like the casing 1, has wide faces and narrow faces, respectively parallel to the wide and narrow faces of the casing; and the apertures 16 are in the two wider sides of the sleeve. The flange or collar 15 is bevelled on the forward face thereof so that it can be pushed in through the open rear end of the sleeve 2, which will yield until the flange comes into the plane of the apertures 16. The flange is thus sprung into position in the sleeve. The elongated screw 14 can be assembled with the piston 11 by rotating it upon the rod 12 of the piston 11, and the screw and piston can be inserted into the carrier together.

The rear end of the long screw 14 is substantially closed, but it gives passage to a stem 17, through an aperture indicated at 18; and the stem 17 is affixed to a rotatable adjusting disc or knob 19 mounted in the rear end of the holder. Both the stem 17 and aperture 18 have a peripheral contour that is square or has some other configuration; so that while the screw 14 can slide on the stem 17, it cannot turn thereon. The disc 19 is milled on its rim and at diametrically opposite points part of the rim is exposed through recesses 20 which are cut in the two wide faces 21 of the casing 1. Through these recesses the disc 19 can be grasped and turned with the fingers to rotate the stem 17, and with it the screw 14. The piston 11 being rectangular in shape of course cannot turn in the rectangular sleeve 2 and when the stem 17 is rotated the screw 14 can be backed up along the rod 12, but does not move longitudinally in the sleeve 2, because of the collar 15 and apertures 16. The result is that the piston 11 is pushed forward, pushing the lipstick out of the end of the sleeve 2 as the lipstick is worn down with use.

At one of the wider sides of the sleeve 2 is a push button 22, which moves in a slot 23 of the wide sides of the casing 1. This slot 23 has countersunk edges to form guides 24 for the button, which overlaps said edges, the button having a projection 25 which is riveted to the sleeve 2.

The casing 1 has a somewhat larger rectangular bore than the cross sectional area of the sleeve 2, so that the latter fits into the casing 1 somewhat loosely but can move freely. It is supported to some extent by the piston 11 together with the rod 12, screw 14 and the stem 17, which projects into the bore 13 of the rod 12. This bore is round and the stem 17 can turn freely therein. The sleeve 2 is also supported adjacent the front end of the casing by parts which control the position of the two sections of the closure of the casing and the parts which secure the two sections of this closure in closed position and cause them to be opened when the sleeve 2 and lipstick 3 are projected.

These parts comprise an enveloping frame member which is made of a bent plate of metal or other suitable material that is substantially tubular and conforms peripherally to the inside of the casing 1. It is designed to fit the casing 1 snugly, as indicated in Figures 7, 8, 9 and 10. This frame has two long sides 26 which fit against the inner surface of the narrower sides of the casing 1, the two sides in question being united along one edge by a third but somewhat shorter side 27 which has the same width as the wider

side of the casing. The sides 26 project past the front end of the side 27. On the opposite side this frame has overturned edges 28 separated by a slot or recess 29. At the front ends the edges 28 of the sides 26 are turned over toward each other as indicated at 30. This frame member, shown fully on a small scale in perspective at Figure 12, extends from the rear end of the casing 1 to the forward or open end thereof in which the bivalve-like shutter is mounted. The bent over edges 30 project into the narrow spaces between the bars 8 and the rear edges of the curved webs 4 of the two sections of the closure, and retain the sections in place.

Cooperating with this frame member is a pair of spring bearing strips 31, each of which is inside said member and in contact with the inner face of one of the sides 26. Each strip 31 has at its front end two resilient fingers or projections 32 and an intervening curved resilient finger 33 of greater length than the fingers 32. The fingers 33 have bent ends 34. The rear ends of the strips or plates 31 are bent over at 35 to engage the rear edges of the sides 26 of the frame member. The length of this member and the strips 31 is such that the fingers 32 rest upon the bars 8, these bars being mounted so that their wider faces are parallel with the length of the device, and the fingers 32 are set so that they press upon said faces of the bars 8 with some force. The middle fingers 33 are curved away from the fingers 32 towards the central longitudinal axis of the holder, clearing both the bars 8 and the overturned edges 30 of the frame member and pressing at their bent out ends 34 upon the inside faces of the curved webs 4 of the closure. When these fingers 33 are pressed outward the closure opens but these fingers 33 are normally set so that they do not press on the inner faces of the closure when the sleeve 2 and the lipstick are not protruding from the casing 1. The outer faces of the casing may of course be milled or otherwise ornamented, as indicated at 36. The strips 31 can be secured to the frame member in any suitable way, to hold the strips 31 to the sides 26, as by making said strips 31 wide enough to fit tightly between said sides, and said member thus serves as an efficient support for said strips to keep them clear of the sleeve 2.

Whenever it is desired to use the lipstick the casing is grasped by one hand and the button 22 pressed forward with the thumb. The sleeve 2 is thus moved and the rounded front end 37 thereof normally in contact with the fingers 33 near their inner ends now presses them outward, causing the sections of the closure to open, as indicated in Figures 6 and 8. The edges of the terminal parts 9 now come together as indicated in Figure 8 at the limit of the opening movement of the closure or shutter and the bars 8 bend the fingers 32 of the strips 31 inward. After the lipstick has been used it is retracted by pushing the button 22 in the opposite direction. As the lipstick is withdrawn as in Figure 7, the fingers 33 return to their original position and the fingers 32 act upon the rear inner corners or edges of the bars 8 with sufficient force to separate the parts or projections 8 and bring the two sections of the closure together along the edges 5.

The rear end of the casing 1 is closed by a cap or plug 38 and the disc 19 has a central aperture in this cap, the latter being countersunk to make a shouldered seat for the disc 19. The boss 39 has a bore 40 which receives a projection 41 on the end of the shank

17 in rigid engagement, keyed together in any suitable way, so that the disc or knob 19 and the stem 17 can be turned together. The inner face of the cap 33 has a recess 42, and on the stem in this recess is a spring 43. The extremity 44 of the tubular screw 14 abuts the spring 43 when the sleeve 2 is withdrawn, this end fitting into the recess 42 and the spring 43 acts to prevent binding of the parts when the disc is actuated.

Having described my invention, what I believe to be new is:

1. A holder comprising a casing with a carrier movably mounted in the casing to protrude at one end thereof, a shutter for the casing, said shutter comprising matched sections to close said end, and resilient fingers mounted in the casing to engage the inner surface of said sections, some of said fingers being set to hold said shutters closed, and the remainder of said fingers being operable by the carrier to separate the sections and open the shutter.

2. The holder according to claim 1 in which the shutter has a bivalve-like form.

3. A holder comprising a casing, a carrier movably mounted in the casing to project at one end thereof, a shutter comprising matched sections movably mounted in the casing to close said end, resilient fingers at said end of the casing in position to press upon the inside surfaces of said sections and operable by the carrier to separate said sections and open the shutter, and resilient fingers in fixed positions at said end of the casing, engaging said sections and normally set to close the shutter.

4. The holder according to claim 3 in which the shutter has a bivalve-like form.

5. A holder comprising a casing, a carrier in the casing mounted to be longitudinally movable to project at one end thereof, a shutter to close said end, a piston in said carrier, a threaded rod on the piston, a threaded element engaging said rod, and a polygonal stem having sliding connection with said element and operable from the opposite end of the casing to adjust the position of the piston in said carrier.

6. A holder comprising a casing, a carrier in the casing and movable longitudinally to project at one end thereof, a shutter at said end of the casing and movable by the carrier to open position, a piston in the carrier having a rod projecting towards the opposite end of the casing, a hollow screw threaded upon said rod, the rod having a hollow bore therein, a stem keyed to said screw for rotating said screw and loosely received in said bore, and a knob at the rear end of the casing rigid with the stem to adjust the position of the piston in the carrier and means on the carrier accessible from the exterior to produce movement of the carrier and piston together.

7. The holder according to claim 6 wherein the screw has an encircling collar and the carrier has apertures to receive the edge of said collar, so that the screw cannot move longitudinally of the carrier, but can rotate therein.

8. The holder according to claim 6 wherein the casing and said carrier are rectangular in cross section.

9. A holder comprising a casing, a carrier mounted in the casing and movable longitudinally to project from one end thereof, a shutter at said end of the casing, said shutter comprising matched sections with flat sides and curved fronts connecting the sides, said sides of each section being flush with the sides of the other section, said sides when the shutter is closed making contact along the front portion of their adjacent edges, said sides having projections at the rear disposed within said end of the casing, the adjacent edges of said sides being divergent when the shutter is closed, the curved fronts terminating adjacent the middle of the sides, a cross bar bridging the sides of each section adjacent the rear edge of the curved front faces, said bars being rectangular with the wider faces thereof substantially parallel to the length of the holder, a supporting frame member in the casing, strips in said frame member extending lengthwise of the casing and having resilient fingers adjacent the shutter which press upon the inner surfaces of the latter, and carrier being movable to actuate said fingers to open said shutter and resilient fingers which engage one of the wider faces of each bar, to hold said shutters closed.

10. A holder comprising a casing, a carrier in the casing movable to project from one end thereof, a shutter in said end of the casing, a framework in the casing enveloping the carrier, the shutter comprising matched sections with flat sides and curved fronts, the sides being extended rearward beyond the rear edges of the curved fronts into said end of the casing, a cross bar connecting the sides adjacent the rear edges of the curved fronts, said framework having overturned front edges which enter the spaces between the fronts of the sections and said bars to hold said sections in place and spring means carried by said frame member and engaging the said sections, some of said spring means being operable by said carrier to cause the shutter to be opened when the carrier is projected, the remainder of said spring means engaging said bar to hold the shutter closed when the carrier is retracted.

11. The holder according to claim 10, wherein said spring elements are carried by strips within the frame member and held in contact with the inner faces of the opposite sides of said member.
